(57) **CLAIM**

I claim the ornamental design for the food chopper blade tray, as shown and described.

DESCRIPTION

FIG. 1 is a top view of the food chopper blade tray;

FIG. 2 is a left side view of the food chopper blade tray, the right side view being a mirror image;

FIG. 3 is a bottom view of the food chopper blade tray;

FIG. 4 is a front view of the food chopper blade tray;

FIG. 5 is a back view of the food chopper blade tray;

FIG. 6 is a perspective view of the food chopper blade tray; and,

FIG. 7 is a perspective view of the food chopper blade tray shown secured within a representative chopping device. The broken lines are for illustrative purposes only and form no part of the design.
